ANGLE POST SHORING HEAD

Takeo Sato, Honolulu, Territory of Hawaii

Application April 29, 1949, Serial No. 90,380

7 Claims. (Cl. 248—357)

1

This invention relates to supporting elements of shoring for reinforced concrete form work, and in particular includes a head for supporting wood beams or blocks on the upper end of an angle post wherein the head is removably mounted on the post and positively secured in position while in use.

The purpose of this invention is to provide a shoring head for extending the effective load bearing area of the upper end of an angle post used in shoring form work for reinforced concrete, in which the head is readily mounted on the post for use and readily removed therefrom after use.

Various devices have been used for extending the load bearing area at the upper end of posts and columns and in permanent construction angles, gusset plates and different shapes are riveted to the upper end of a post or column which provides a positive connection and extended load bearing areas; but where removable shoring heads are used in concrete form work it is difficult to provide a positive or rigid connection that eliminates overhung or eccentric strain and sidewise movement between the supporting elements and form. With this thought in mind this invention contemplates oppositely positioned vertically disposed webs with an upper bearing plate and with comparatively thick vertically disposed base elements with angle receiving pockets in the elements and set screws in the said base plates.

The object of this invention is, therefore, to provide means for forming a shoring head that may be rigidly mounted on the upper end of an angle post formed with two oppositely positioned angles, wherein the head may be removed from the post after use.

Another object of the invention is to provide a shoring head for angle posts that may readily be attached to the post in the field by the average workman.

A further object of the invention is to provide a shoring head for angle posts which is of a comparatively simple and economical construction.

With these and other objects in view the invention embodies an elongated vertically disposed web formed with two offset sections with thick vertically disposed base elements having sockets for set screws for holding the head in position on two oppositely positioned angles, and an upper horizontally disposed plate with upwardly extended flanges at the sides.

Other features and advantages of the invention

will appear from the following description taken in connection with the drawings wherein

Figure 1 is a side elevational view illustrating the shoring head in position on the upper end of an angle post with a wood beam carried by the horizontally disposed plate of the shoring head.

Figure 2 is a cross section taken on line 2—2 of Figure 1 looking upwardly toward the underside of the shoring head.

Figure 3 is a cross section through the shoring head taken on the line 3—3 of Figure 1.

Figure 4 is a plan view of the shoring head with the angle attaching elements on the underside thereof shown in dotted lines.

Figure 5 is an end elevational view of the shoring head.

Referring now to the drawings wherein like reference characters denote corresponding parts the angle post shoring head of this invention includes a horizontally disposed load carrying plate 10 having upwardly extended flanges 11 and 12 at the sides, vertically disposed longitudinally extended offset webs 13 and 14 extended downwardly from the under surface of the plate 10, and comparatively thick base elements 15 and 16, of the webs 13 and 14, respectively, and set screws 17 and 18 with extended ends 19 and 20 and screwdriver slotted heads 21 and 22, respectively.

The flanges 11 and 12 of the plate 10 are provided with openings 23 and 24 for nails 25 and, as illustrated in Figures 1 and 3 the wood beam or block 26 is positioned on the shoring head or saddle and the nails are driven into place as shown.

The webs 13 and 14 which extend downwardly from the plate 10 are provided with ribs 27 and 28, which have grooves 29 and 30, respectively in their inner surfaces for receiving the edges 40 of the legs or flanges of the angles of the posts, as indicated by the numerals 31 and 32. The outer ends of the base elements 15 and 16 are also provided with extended ribs or flanges 33 and 34 with sockets 35 and 36 having extended edges 37 and 38, respectively, as shown in Figure 2. With the angle holding sockets formed in this manner the shoring head is slid downwardly over the ends of the angles of the posts and with the legs of the angles secured in the sockets the shoring head is rigidly mounted on the end of the post. The legs of the angles of the posts are provided with openings 39 which are positioned at spaced intervals and with the last of the openings spaced from the upper ends 50 of the angles of the posts a distance equal to the

distance from the centers of the set screws 17 and 18 from the lower surface of the plate 10, the ends 19 and 20 of the set screws, which are positioned in threaded openings 40 and 41 of the base elements, will extend into openings of the legs of the angles as shown in Figure 2.

With the parts arranged in this manner the improved shoring head of this invention is readily attached to the end of an angle post by sliding the ends of the angles into the sockets in the under side of the head and screwing the set screws inwardly with the ends 19 and 20 securing the head on the end of the post.

It will be understood that modifications may be made in the design and arrangement of the parts without departing from the spirit of the invention.

What is claimed is:

1. A shoring head for angle posts comprising an elongated plate having offset vertically disposed longitudinally extended oppositely positioned webs with base elements on the inner ends thereof extended downwardly therefrom, and means removably attaching the said head to the end of an angle post having angles positioned corner to corner through the said offset webs and base elements.

2. A shoring head for angle posts comprising an elongated plate having offset vertically disposed longitudinally extended oppositely positioned webs with base elements on the inner ends thereof extended downwardly therefrom, said base elements having threaded sockets therein, and set screws in the said threaded sockets of the base elements with extended ends for securing the head on the end of the angles of a post, in which the angles are positioned diagonally and back to back.

3. A shoring head for angle posts comprising an elongated plate having offset vertically disposed longitudinally extended webs with base elements on the inner ends thereof extended downwardly therefrom, said offset webs and base elements having angle receiving sockets therein, and set screws threaded in the said base elements for securing the ends of angles of an angle post in said sockets.

4. A shoring head for angle posts comprising an elongated plate having offset vertically disposed longitudinally extended oppositely posi-

tioned webs with base elements on the inner ends thereof extended downwardly therefrom and means removably attaching the said head to the end of an angle post having angles positioned corner to corner through the said offset webs and base elements, said elongated plate having flanges extended upwardly from the opposite sides thereof and said flanges having nail receiving openings therein.

5. A shoring head for angle posts comprising an elongated plate having offset vertically disposed longitudinally extended oppositely positioned webs with base elements on the inner ends thereof extended downwardly therefrom, means removably attaching the said head to the end of an angle post formed with angles positioned back to back and in opposed relation through the said offset webs and base elements, and means attaching the said elongated plate to a beam of a form.

6. A shoring head for angle posts comprising an elongated plate having offset vertically disposed longitudinally extended webs with base elements on the inner ends thereof extended downwardly therefrom, said webs and base elements thereof having ribs thereon for receiving the ends of angles of an angle post, and set screws securing the head to the angles of the post.

7. A shoring head for angle posts comprising an elongated plate having offset vertically disposed longitudinally extended webs with base elements on the inner ends thereof extended downwardly therefrom, said webs and base elements thereof having ribs with overlapping edges thereon for receiving the ends of angles of an angle post, and set screws securing the head to the angles of the post.
